UNITED STATES PATENT OFFICE.

FRANK C. WHITE, OF MERIDEN, CONNECTICUT, ASSIGNOR TO THE WILCOX & WHITE COMPANY, OF MERIDEN, CONNECTICUT, A CORPORATION OF CONNECTICUT.

AUTOPNEUMATIC MUSIC-PLAYING INSTRUMENT.

No. 862,429.

Specification of Letters Patent.

Patented Aug. 6, 1907.

Application filed December 12, 1906. Serial No. 347,414.

To all whom it may concern:

Be it known that I, FRANK C. WHITE, a citizen of the United States, residing at Meriden, New Haven county, Connecticut, have invented certain new and useful Improvements in Autopneumatic Music-Playing Instruments, of which the following is a full, clear, and exact description.

My invention relates to improvements in auto-pneumatic music-playing instruments.

10 The object of the invention is to provide means whereby a solo or melody note can be caused to sound out above the other notes which are intended to accompany the same.

15 The operation is novel and is under manual control to such a degree that the power of the solo note may be varied as desired. In the apparatus I employ the same or equivalent apparatus as that shown in my application Serial No. 341,054, filed October 29, 1906, wherein I have described means whereby the operator may, by 20 a quick or abnormal impulse on the pedal, change the tension in the wind chest from low to high for the purpose of accenting certain notes. In my present improvement, even though a plurality of notes are to be struck at one time, any one or more of said several 25 notes may be caused to ring out more vigorously than the others.

In the accompanying drawings; Figure 1 is a longitudinal section, the parts being diagrammatically arranged, only such parts being shown as are necessary 30 to illustrate the invention. Fig. 2 is a cross sectional view.

1 is what is termed an "equalizer" bellows.

2 is a foot bellows or "feeder" so called, distended by pedal 3 through suitable connecting mechanism.

35 4 is a spring normally causing the bellows 2 to collapse against the action of pedal 3.

5 is a spring to yieldingly distend equalizer bellows 1.

6 is a main chamber in an exhaust trunk or "wind chest".

40 7-7^a are separate "action divisions". Any desired number of action divisions may be employed.

8-8^a are valves located in passages connecting the space 6 with the action division 7-7^a respectively.

45 9-9^a are valves controlled by pneumatics 10-10^a respectively. These valves are adapted to passages connecting the action divisions 7-7^a respectively with a high tension exhaust chamber or space 11. This chamber 11 is in direct communication with the bellows 2 by means of a passage 12 and space 15. The 50 main exhaust chamber 6 is in direct communication with the interior of the equalizer bellows 1 by means of passage 13.

14 is a throttle valve.

14^a are bleed-holes in said valve 14 arranged in a pas-

sage connecting the interior of equalizer bellows 1 with the space 15 leading to bellows 2.

16 is a duct leading from pneumatic 10 to a supplemental or marginal perforation 17 in tracker 18.

19 is a duct leading from pneumatic 10^a to another such perforation 17^a in the tracker 18.

20-20^a are ducts leading from the action divisions respectively to the action mechanism, the number of said ducts corresponding to the number of key actions employed.

In Fig. 2 I have shown a single key action in which one of the ducts 20^a is shown as leading thereto. It is unnecessary to describe in detail the key action, because the same is well understood. It is sufficient to say that it includes ordinarily a power pneumatic 21 operating a hammer 22, which in turn operates a key 23 70 or sounding device at the proper time. 24 is a duct from the tracker-board leading to one of the primary pneumatics for an individual key action.

The operation is as follows: Air is exhausted from the several action divisions 7-7^a by means of bellows 2. 75 For operation of the actions under normal tension the course of the air being exhausted is past valves 8-8^a through chamber 6, passage 13 and bellows 1, and past valve 14 through space 15 and out through feeder bellows 2. Normally both valves 9-9^a will stand closed, 80 and since the valves 8-8^a open freely toward the chamber 6, the same degree of tension will be found in the action divisions 7-7^a as will be found in the equalizer bellows 1.

The operation of the valve or throttle 14 is substantially as follows:—When the operator starts to exhaust the air, it will be exhausted from space 15 and the passage communicating to valves 9-9^a and at the same time air will be exhausted from equalizer bellows 1, through bleed-holes 14^a. When the pull of the bellows 90 1 occasioned by spring 5 overbalances the normal pull of the feeder bellows 2, or is slightly in excess thereof, this valve or throttle 14 will open slightly or sufficiently to permit the equalizer to perform its function of maintaining through passage 13 a uniform tension. As in my former application, above referred to, if an abnormal impulse is given to feeder bellows 2, the violence of said impulse will momentarily close valve 14, thus temporarily permitting a very much higher tension in the space 15 than within the feeder bellows, the degree 100 of variation being determined by the force of the abnormal pressure.

If the solo note to be struck is controlled from action division 7^a, the marginal opening 17^a will be exposed at the same time that said note is to be struck, or just before. The opening of duct 17^a will cause pneumatic 10^a to open valve 9^a (see Figs. 1 and 2) and the higher tension of the foot bellows 2 will be instantly produced

within the action division 7^a because said bellows will then be in direct connection with chamber 7^a and any action pneumatic open to division 7^a for example will then be operated with a degree of force proportional to 5 the increased tension in bellows 2. Other action pneumatics open to division 7 and arranged to be simultaneously struck will be struck with that lesser degree of tension found in equalizer bellows 1.

In the drawings section 7^a represents the treble action 10 division and 7 the base action division. When high tension is desired in either of the action divisions (according to which action is to produce the solo note), the valve which cuts off that division from high tension space 11 will be opened and at that instant, of course, 15 the valve in said division leading to space 6 will automatically close. High tension might be had in all action divisions at once by merely putting all of the divisions in direct communication with bellows 2.

As explained in my former application an abnormal 20 operation of the exhaust bellows 2 will cause the valve 14 in the equalizer chamber to momentarily close, at that moment, therefore, the full abnormal or high tension will be secured in any one of action divisions which may be in communication with said exhaust bellows at 25 that time. As before explained any desired number of action divisions 7^a may be employed. They might be multiplied to such an extent that there would be an action division for each key action. Very satisfactory results can be obtained by a comparatively few divisions, the idea being merely to provide a sufficient 30 number of divisions so that a sufficient number of accompaniment notes may be employed without using

any notes in that division in which the solo note is to occur.

What I claim is:

1. In an auto-pneumatic music playing instrument, a tracker-board, an exhaust bellows, a divided wind-chest, a high tension chamber and a low tension chamber, an equalizer for the latter, passages from the several divisions of the wind-chest into the low tension chamber, valves 40 therein freely opening toward the equalizer, passages from the high tension chamber to each division of the wind-chest, valves therein closing toward the exhaust mechanism, pneumatics for opening the latter valves, ducts leading from said pneumatics to the tracker-board, and arranged to be opened and closed by a perforated note-sheet 50 adapted to traverse the tracker-board, a check valve for the equalizer, a bleed-hole or vent for said equalizer connecting the same with the exhaust bellows, and series of action mechanisms in communication with the wind-chest, and valves therein controllable from the tracker-board.

2. In an auto-pneumatic music playing instrument, a tracker-board, an exhaust bellows, a divided wind-chest, a high tension chamber and a low tension chamber in communication with all of the divisions in said wind-chest, 55 valves therefor, a passage leading from the exhaust to the low tension chamber, an equalizer therein, a check valve between the equalizer and the exhaust bellows, a bleed-hole between said equalizer and exhaust, a passage from said exhaust to said high tension chamber, means for 60 operating the valves in the passages from the high tension chamber to the several divisions in the wind-chest said means being controllable from the tracker-board, a series of action mechanisms in communication with the wind-chest, and valves therein controllable from the tracker-board.

FRANK C. WHITE.
